FACE PLATE

James C. Prior, Gardena, Calif., assignor to Sierra Electric Corporation, Gardena, Calif., a corporation of California

Application January 27, 1959, Serial No. 54,348

Term of patent 14 years

(Cl. D26—13)

Fig. 1.

Fig. 2.

Fig. 3.

Fig. 1 is a front plan view of the face plate showing my new design;

Fig. 2 is a side elevational view thereof, both sides appearing the same; and

Fig. 3 is an end view thereof, the opposite end appearing the same.

The characteristic feature of the design lies in the slightly raised central portion extending transversely entirely across the plate and occupying approximately one-third of the plate substantially as shown.

I claim:

The ornamental design for a face plate, substantially as shown, and described.
